FIRE DETECTOR OR THE LIKE

Nagao Abe, Tokyo, Japan, assignor to Nittan Company,
Limited, Tokyo, Japan, a corporation of Japan

Filed June 14, 1968, Ser. No. 12,370

Claims priority, application Japan Dec. 27, 1967

Term of patent 14 years

Int. Cl. D29—01

U.S. Cl. D72—1

FIG. 1

FIG. 2

FIG. 3

FIGURE 1 is a front perspective view, seen from below, of the fire detector or the like, showing my new design;

FIG. 2 is a front perspective view, seen from above, thereof; and

FIG. 3 is a bottom plan view thereof.

The rear of the fire detector or the like is substantially identical with the front thereof.

The dominant feature of my design resides in the portions shown in full lines.

I claim:

The ornamental design of a fire detector or the like, as shown and described.
